UNITED STATES PATENT OFFICE.

MICHAEL PARIDON, OF BARBERTON, OHIO, ASSIGNOR TO THE DIAMOND MATCH COMPANY, OF CHICAGO, ILLINOIS, A CORPORATION OF ILLINOIS.

MEANS FOR APPLYING MATCH-IGNITION MATERIAL TO BOOK-MATCHES, &c.

1,247,995.

Specification of Letters Patent. Patented Nov. 27, 1917.

Application filed June 15, 1916. Serial No. 103,905.

To all whom it may concern:

Be it known that I, MICHAEL PARIDON, a citizen of the United States, and resident of Barberton, in the county of Summit and State of Ohio, have invented certain new and useful Improvements in Means for Applying Match-Ignition Material to Book-Matches, &c., of which the following is a specification.

10 This invention relates to means for applying ignition material to match-book covers and the like, having reference more especially to mechanism for use in connection with or as a unit of the match-book 15 making machine illustrated in Letters Patent of the United States No. 1,042,472 dated October 29, 1912.

In the said patented machine a succession of match books, comprising match 20 cards with covers fastened thereto, are transported in close relation to the periphery of a rotating roller by means of which a quantity of ignition paint is transferred from a tank or container to the external 25 surface of the fastened cover fold. The books are spaced apart in the successive links of an endless carrier, and hence as the leading edges of the book covers successively meet the periphery of the rotating 30 roller "paint" is scraped up by such edges and deposited upon the inner surface of each of the covers before the application of the substance to its external surface.

The primary object of my invention is to 35 provide simple and efficient mechanism whereby a coat of ignition substance is applied to the external surface only of a book cover or the like.

Another object of the invention is to provide simple and efficient means whereby the 40 ignition substance, when it is applied to the cover, is uniformly distributed thereon in such a manner as to present a smooth and even match striking surface.

45 With these and other objects in view my invention, generally stated, comprises, first, a plurality of rotary elements for applying the ignition substance to the external surface of traveling covers; secondly, a vibratory element for evenly distributing such substance on the surface to which it has been applied; and, finally, various novel features of construction and combinations of parts, all of which will be hereinafter 50 described and claimed.

In the annexed drawings—

Figure 1 is a side elevation partly in section of "paint" applying and distributing mechanism embodying a preferred form of my invention, showing a portion of 60 the match-book carrier, and adjuncts.

Fig. 2 is a plan of the paint applying mechanism, with the carrier removed, excepting one link thereof.

Fig. 3 is a longitudinal vertical section, 65 through the paint applying mechanism, as on the line 3—3 of Fig. 2, showing a section of the carrier, and the match-books therein.

Fig. 4 is a transverse vertical section, as 70 on the line 4—4 of Fig. 3.

Fig. 5 is a perspective view of one of the links of the carrier, showing a match-book therein.

Fig. 6 is a similar view of one of the 75 match-books.

Fig. 7 is a diagram showing the operation of the first paint applying brush on the cover fold of a match book.

Figs. 8 and 9 are diagrams showing the 80 operation of the second brush on the same cover fold.

Referring to the drawings, 10 designates a section of a preferred form of feeder for a succession of match-books. This form of 85 feeder comprises an endless flexible carrier composed of hingedly connected link members in which the match cards and covers (with the end folds of the latter projecting beyond the carrier) are assembled and 90 bound together in book-like form; thence transported to and past a structure whereby frictional ignition substance of the consistency of paint is applied exteriorly to the under surfaces of the projecting end 95 folds of the covers, and thence carried through an extended drying bath.

The "paint" applying structure herein illustrated as embodying my invention includes a plurality of oppositely-rotating 100 elements which are arranged in spaced relation to each other directly beneath the path of the underside of the projecting end folds of the covers on the carrier, whereby said elements impinge against each of such 105 folds at different points of its travel; one element contacting with the fold at or near its leading end and moving onward therewith so as to apply the paint to the adjacent traveling part of the fold, and the 110

other element contacting with the fold adjacent the inner edge of the partially painted surface thereof and applying the paint with a stroke in an opposite direction to that of the first element, thus efficiently coating the fold from end to end and yet avoiding any liability of depositing paint upon the inner surface of the leading end of the fold.

- 10 The rotary paint-applying elements preferably embody two brush structures comprising segmental brush-portions 11, 11' of appropriate width and length arranged on the peripheries of discal bodies 12 fast on parallel shafts 13 having their bearings in spaced posts 14 which are secured to a suitable standard 15. These posts are provided with bracket extensions 16 which support a track section 17 for the carrier.
- 15 Beneath the paths described by the respective brushes during their rotation are rollers 18 which are mounted to rotate with their lower portions within a vessel 19 containing the ignition composition or "paint".
- 20 The rollers are carried by shafts 20 having their bearings in the posts 14, which rollers in their rotation, carry up a quantity of paint from the vessel into the paths of the brushes, and the latter in their downward and upward travel sweep upon the peripheries of the respective rollers and take therefrom sufficient paint for application to the cover folds of the match books.

The rollers and brushes may be concurrently rotated by any suitable mechanism. In the present instance each of the brush shafts 13 is provided at one end with a gear wheel 22, and each of the roller shafts 20 is provided with a similar wheel 23. Affixed to a post 24 adjacent the vessel are two stud shafts carrying co-acting idler gears 25 which mesh with the respective gears 23 on the roller shafts. The latter gears mesh with adjacent gears 26 fast on shafts 27 having their bearings in boxes on posts 28 rising from the standard 15. These shafts 27 are also equipped with gear wheels 26' which mesh with the gears 22 on the respective brush shafts. One of the shafts 27 bears a sprocket wheel 29 which is connected with and driven from a suitable source of power, and hence the entire gear train is driven in such a manner that the rollers 18 are concertedly rotated in opposite directions to each other and the brushes 11, 11' similarly in opposite directions to each other, as indicated by the arrows in Fig. 3.

On one of the brush shafts 13 is a gear wheel 30 which extends through an opening 31 in the floor of the track section 17 and meshes with the adjacent teeth of the carrier, thereby impelling the latter continuously.

The relation of the brushes to each other and to the links of the carrier are such that

as the projecting end fold 32 of each book cover passes over the first brush (11) the latter in its rotation impinges against the leading end of the fold, as at the point *a*, Fig. 7, and in its travel with the fold applies a coat of paint to that part of the surface of the fold between the points *a* and *b*; and that as the partially-painted fold passes over the second brush (11') the latter in its rotation impinges against the body of the fold, as at the point *c*, Fig. 8, and in its travel, which is in a direction opposite to that of the fold, applies a coat of paint to the surface of the fold between the points *d* and *e*, as indicated in Fig. 9. This successive painting operation of the two brushes takes place upon the under surfaces of the end folds of the succeeding covers, during the continuous operation of the machine; the rotating segmental brushes escaping the spaces between adjacent books.

After leaving the paint-applying mechanism the books are carried in a vertical path by the carrier; suitably-disposed lower and upper guide wheels 33, 34 (Fig. 1) respectively, for the carrier being provided. These wheels are borne by shafts 35 having their bearings in brackets 36 on the usual frame posts 37 of the machine. Adjacent the ascending run of the carrier I have mounted simple and efficient means for effecting the uniform distribution of the wet "paint" upon the cover folds of the traveling books, in order that the paint when dry shall present a smooth and even match-striking surface. Such paint-distributing means, in its preferred form, comprises a pendant arm 38 which is pivoted at its upper end to a bracket 39 on one of the supporting posts 37, so that the lower portion 105 of the arm may be rapidly vibrated toward and from the path of the carrier. This lower portion bears on its inner side an elongated paint distributing element, preferably in the form of a brush 40, which is so disposed that by the vibratory action of the arm the brush is caused to impinge with a spreading effect against the painted surfaces of the succeeding match-books and thus insure the even distribution of the paint as above mentioned. Although any suitable means may be employed for vibrating the arm, I prefer to employ for this purpose devices of the character illustrated in the drawings; that is to say, the arm is 110 provided with a suitably-disposed anti-friction roller 41 with which co-acts the toothed or serrated periphery of a wheel 42 fast on the shaft 35 of the upper guide wheel; said roller being maintained yieldingly in contact with the wheel 42 by means of a suitably-disposed retracting spring 43. The upper wheel 34 is rotated by the frictional contact therewith of the traveling chain, and hence the motion is transmitted 115 120 125 130

through the upper shaft 35 to the toothed wheel. Since this wheel is relatively large and bears a multiplicity of peripheral teeth or projections, it follows that the spring-pressed roller, and, perforce, the arm and brush, are rapidly vibrated in relation to the ascending books on the carrier.

It is to be understood that I do not limit myself to the specific mechanisms herein shown and described to exemplify the principle of my invention, as such mechanisms may be variously modified within the scope of the appended claims.

I claim—

15. 1. The combination, with means for concurrently feeding a succession of flat-surfaced articles, of means for applying ignition material to the corresponding surfaces of the succeeding traveling articles, said means comprising a plurality of material-applying elements arranged in spaced relation to each other adjacent the path of such surfaces, and means for moving said elements in opposite directions to each other 20 and in synchronism with the traveling articles, whereby one element contacts with each article at or near the leading end of the latter and travels therewith so as to apply a partial coat of ignition material 25 to the adjacent surface of the article, and the other element subsequently contacts with each partially-coated surface at a point between the ends of the article and travels oppositely thereto so as to complete 30 the coating of the surface.

2. The combination, with means for concurrently feeding a succession of flat-surfaced articles, of means for applying ignition material to the corresponding surfaces 40 of the succeeding traveling articles, said means comprising a plurality of material-applying elements mounted to rotate in spaced relation to each other adjacent the path of such surfaces, and means for rotating 45 said elements in opposite directions to each other and in synchronism with the traveling articles, whereby one element contacts with each article at or near the leading end of the latter and travels therewith so as to apply a partial coat of ignition material 50 to the adjacent surface of the article, and the other element subsequently contacts with each partially-coated surface at a point between the ends of the article and travels 55 oppositely thereto so as to complete the coating of the surface.

3. The combination, with means for concurrently feeding a succession of flat-surfaced articles, of means for applying ignition material to the corresponding surfaces 60 of the succeeding traveling articles, said means comprising a plurality of segmental material-applying elements mounted to rotate in spaced relation to each other adjacent the path of such surfaces, and means

for rotating said elements in opposite directions to each other and in synchronism with the traveling articles, whereby one element contacts with each article at or near the leading end of the latter and travels 70 therewith so as to apply a partial coat of ignition material to the adjacent surface of the article, and the other element subsequently contacts with each partially-coated surface at a point between the ends of the 75 article and travels oppositely thereto so as to complete the coating of the surface.

4. The combination with means for concurrently feeding a succession of flat-surfaced articles, of means for applying ignition 80 material to the corresponding surfaces of the succeeding traveling articles, said means comprising a plurality of rotary segmental brushes arranged in spaced relation to each other adjacent the path of such surfaces, 85 a container for ignition material, means for conveying such material to the paths of the respective brushes, means for actuating the conveying means, and means for rotating said brushes in opposite directions to 90 each other and in synchronism with the traveling articles, whereby one brush contacts with the adjacent surface of each article at or near the leading end of the latter and travels therewith in a manner to apply 95 a partial coat of ignition material to the article, and the other brush subsequently contacts with each partially coated surface and travels oppositely thereto in a manner to complete the coating of the surface. 100

5. The combination with a carrier for a succession of separated match books, of segmental brushes arranged in spaced relation to each other, and means for rotating said 105 brushes in opposite directions to each other and in synchronism with the carrier whereby said brushes act upon each of the traveling books and escape the spaces therebetween, one brush contacting with each book 110 at or near the leading end of the latter and traveling therewith so as to apply a partial coat of ignition material to the adjacent surface of the book and the other brush subsequently contacting with each partially-coated surface at a point between the ends 115 of the book and traveling oppositely thereto so as to complete the coating of the surface, together with means for supplying ignition material to said brushes. 120

6. The combination with a carrier for a succession of separated match books, of segmental brushes arranged in spaced relation to each other, and means for rotating said 125 brushes in opposite directions to each other and in synchronism with the carrier whereby said brushes act upon each of the traveling books and escape the spaces therebetween, one brush contacting with each book at or near the leading end of the latter and 130

traveling therewith so as to apply a partial coat of ignition material to the adjacent surface of the book and the other brush subsequently contacting with each partially-coated book at a point between the ends of the book and traveling oppositely thereto so as to complete the coating of the surface, a container for ignition material, rollers for conveying such material to the paths of the 10 respective brushes, and means for rotating said rollers.

7. The combination with a flexible carrier for a succession of articles, and guide wheels for the carrier, of means for applying a

coat of ignition material to said articles, 15 a pivoted arm adjacent the path of the articles after they have been coated, said arm having a distributing portion arranged to contact with the coated surface, a toothed wheel actuated through one of the guide 20 wheels for the carrier, and operative connection between said toothed wheel and the pivoted arm.

Signed at Barberton in the county of Summit and State of Ohio this 12th day of 25 June A. D. 1916.

MICHAEL PARIDON.
